UNITED STATES PATENT OFFICE.

FRANK G. PERKINS, DECEASED, LATE OF LANSDALE, PENNSYLVANIA, BY GERTRUDE S. PERKINS, EXECUTRIX, OF SOUTH BEND, INDIANA, ASSIGNOR TO PERKINS GLUE COMPANY, A CORPORATION OF PENNSYLVANIA.

GLUE-APPLYING APPARATUS.

1,280,288.

Specification of Letters Patent.

Patented Oct. 1, 1918.

Application filed June 15, 1917. Serial No. 174,999.

To all whom it may concern:

Be it known that FRANK G. PERKINS, deceased, late a resident of Lansdale, borough of Lansdale, State of Pennsylvania, did invent certain new and useful Improvements in Glue-Applying Apparatus, of which the following is a specification.

The invention relates to improvements in glue applying apparatus. Prior to the present invention, it was common to apply glue to wood veneers, etc., by carpet rolls. Such rolls are quite inadequate for certain glues, particularly a glue such as described in Reissue Letters Patent 13,436 and Letters Patent 1,020,656, 1,078,691, 1,078,692 and 1,200,488. The main object of the present invention is to provide a roll and apparatus which will practically apply such heavy viscous glues which are similar to high grade animal glues for gluing up furniture veneers and the like. This application is a continuation in part of copending application which resulted in the granting of the United States Letters Patent No. 1,238,810 September 4, 1917. According to the present invention, the glue roll is corrugated or grooved in a special way and so constructed that a substantially continuous coating of such heavy viscous glue may be applied as the roll revolves, but in a sufficiently thin layer to prevent any material amount of the glue being wasted an adjustable scraper being provided to regulate the exact amount of glue applied.

In the accompanying sheet of drawings which forms a part of this specification, Figure 1 is a vertical section through a glue spreader adapted to operate rolls according to the present invention, and Figs. 2 to 6 inclusive illustrate the grooving of such rolls.

Referring to Fig. 1, 1 represents a suitable frame, in which is journaled a lower glue applying roll 2. Situated below the roll 2 and extending the whole length of the same is a lower glue trough 3 for applying glue to the cylindrical surface of roll 2. Glue trough 3 has an opening in its bottom for withdrawing glue from the trough, this opening being normally covered by a gate 4, hinged at 5 and provided with a handle for moving the gate. Extending up through the

bottom of the glue trough 3 are two steam pipes 7, which connect with an enlarged steam pipe or cylinder 8, extending longitudinally in the glue trough 3 for the purpose of supplying steam or hot water to heat or keep the glue warm within the trough 3. At the front side of the machine there is provided a member 9, the top of which forms a table on which the material to be glued may rest when it is being admitted to the machine. The member 9 has one part thereof forming a substantial extension for the front side of the glue trough 3 and is pivotally mounted on the main frame 1 at 10. The member 9 carries on its inner end a scraper 12, adapted to remove the surplus glue from the roll 2, as it revolves and regulate the amount of glue applied. At each end of the machine there is provided a stop 13, on the main frame 1, and coöperating therewith and passing vertically through the member 9 at some distance from the point 10 are adjusting set screws 14, provided with locking nuts 15. By adjusting the position of the set screws 14 within the member 9, the position of the scraper 12 in respect to the surface of the glue roll 2 may be adjusted as desired and the downward movement of the scraper 12 toward the glue roll 2 may be limited to any desired position. Pivotally mounted on the main frame 1 and on the shaft 16 is a frame 17. The shaft 16 is above or at one side of a vertical plane through the axis of roll 2. Journaled in the frame 17, above the roll 2, is an upper glue applying roll 18. Rigidly fixed to frame 17 and coöperating with the roll 18 are the ends 19 of an upper glue applying trough for the glue roll 18. The rear side of this trough 20 is also rigid with the frame 17, and the rear side 20 is provided with a bulging portion 21. The front side of the upper glue trough consists of a member 22, hinged to the ends 19, as by a shaft 23. The front side 22 of the upper glue trough also carries a portion forming the bottom 24 of the glue trough, which, in turn, carries a scraper 25 for the upper glue roll. At the lower portion of the upper glue trough is provided a rod 26, which, together with shaft 23, serves to hold the ends 19 of the upper glue trough in position. Extending downwardly from

the member 22 are lugs 27 at each end of the machine, through which pass set screws 28, coöperating with stops 29 upon the end pieces 19. By means of the set screws 28 and 5 stops 29 the position of the front wall of the upper glue box may be adjusted as desired, and consequently the movement of the scraper 25 toward the upper glue roll 18 may be limited and adjusted to any desired position.

For the purpose of holding the scrapers 25 in the adjusted position with respect to the glue roll 18, there is provided at each end of the machine a swinging member 30, 15 swinging about a bent portion 31 as a pivot. Bent portions 31 of the arms 30 are passed into the front wall 22, inside of the upper glue trough. The arms 30 are adapted to seat in recesses in the member 20 and the 20 arms 30 are provided with nuts 33 on their outer ends, so that when the arms 30 are seated in the recesses 32 the nuts 33 may be turned and thus draw the member 22 and scraper 25 inwardly until the set screw 25 engages the stop 29 to limit the movement of the scraper toward the upper glue roll and hold it in its adjusted position. When it is desired to release the front member 22 and the scraper 25, it is only necessary to give the nuts 33 a slight turning movement, when the arms 30 may be thrown upwardly and swung about their pivots 31, thus releasing the entire front wall 22 and the scraper 25, so that it may be easily 35 moved backward and away from the roll 18 as far as desired. Similar arms and nuts may be provided for holding the lower scraper 12 in position.

For the purpose of heating the glue with- 40 in the upper glue trough, the front wall 22 is provided with a hollow portion therein 37, extending substantially the whole length of the upper trough. Steam pipes 38 are provided for supplying steam or hot water 45 to this space 37 in order to properly heat the glue in the upper trough. Rigid with the pivoted arm 17 and extending in the opposite direction from the shaft 16 are arms 39, one at each end of the machine. 50 Also fixed, one to each end of the main frame of the machine, as at 41, are rods 40, which extend upwardly and pass through apertures in the arms 39. Above the arms 39 the rods 40 are provided with adjusting 55 nuts 42 carrying hand wheels 43, the nuts 42 resting in cup shaped depressions in the ends of the arms 39. The length of the arms or rods 40 may be adjusted by inserting spacing members 44 between the nuts 45 60 on the ends of the rods 40 and the lugs 41 on the main frame of the machine.

It will therefore be seen that by merely turning the hand wheels 43 the arms 39 will be moved upwardly or downwardly, as desired, thus at the same time moving the

upper glue roll 18 so that the space between it and the lower glue roll 2 may be adjusted as desired.

In order to help force the upper glue roll downwardly toward the lower glue roll 2, 70 there is provided a clip 46 extending over the ends 19 at each end of the machine, to each of which clips are bolted rods 47. The lower ends of the rods 47 are pivotally connected to a lever member. One end of the 75 lever member is held in fixed position by means of a rod 50, secured to the floor or base of the apparatus. The lever is pivoted to the upper end of the rod 50 to form a fulcrum point. At the outer end of the 80 lever or at the end of its long arm, there is connected an adjustable weight or weights 51. It will therefore be seen that the weights 51, pulling downwardly on the arm and rods 47, which are connected to the ends 85 19 of the frame 17, tend to force that portion of the frame 17 carrying the upper glue roll 18 downwardly and toward the lower glue roll. By adjusting the size and weight of the weights 51 the pressure which 90 the upper glue roll 18 exerts downwardly may be adjusted as desired. For driving the apparatus there is provided a main driving wheel 52, suitably journaled to the main frame. The driving wheel 52 is fixed to a 95 shaft 53, which carries a gear wheel, which, in turn, meshes with a gear wheel 55 secured to the lower glue roll 2, for the purpose of driving the same. The upper glue roll 18 is driven from the shaft 53 by any 100 suitable connecting driving devices.

In order that the glue may be applied properly to the wood or other material when run through the apparatus between the rolls, the rolls are grooved or corrugated. As illustrated in Figs. 2 to 6, the rolls are grooved longitudinally, the grooves being substantially parallel to one another.

As illustrated in Fig. 2 there are about 8½ grooves to the inch, the grooves being 110 about .08 inch wide at the top and about .04 inch deep, the parts between the grooves having substantially flat faces about .04 inch wide which are adapted to engage the material operated upon or being glued.

In Fig. 3, there are about 10 grooves to the inch, the grooves being about .06 inch wide at the top and about .04 inch deep with the intermediate substantially flat faces about .04 inch wide.

In Fig. 4, there are 10½ grooves to the inch, about .05 inch wide and about .06 inch deep with intermediate flat faces about .04 inch wide.

In Fig. 5 there are 11 grooves to the inch, 125 the grooves being about .045 inch wide and about .04 inch deep with the intermediate flat faces about .045 inch wide.

In Fig. 6, there are about 12 grooves to the inch, the grooves being about .04 inch 130

wide at the top and about .025 inch deep with intermediate faces about .043 inch wide.

As shown in Fig. 2 herein, the grooves are indicated at 71 and the intermediate flat faces at 70. In most of the figures the grooves are shown with their side walls having a substantial taper outwardly so that the grooves are wider at the top than at the bottom. This permits the glue to be more easily 10 and uniformly withdrawn therefrom. For similar reasons it is preferable to provide the bottoms of the grooves with curved bottoms as illustrated in Figs. 2 to 6. It is desirable that there be some substantially flat 15 face between the grooves in order that the roll will not bite into the wood or other material to an undesirable extent.

The grooves should be between 6 and 16 to the inch, from .02 inch to .06 inch deep, 20 from .03 inch to .08 inch wide at the top. Preferably there should be over 8 and not over about 12 to the inch as illustrated in Figs. 2 to 6, and when the grooves are about 25 10 to the inch, about .04 inch or more deep, about .05 inch wide at the top, as illustrated in Figs. 3 and 4, they serve admirably for general use.

What is claimed as new and desired to be secured by Letters Patent is:

30 1. The combination of a glue applying roll grooved longitudinally and arranged to apply the glue evenly and directly to the surface to be glued, the grooves having curved bottoms which merge into the side 35 walls thereof, the side walls tapering outwardly so that the grooves are wider at the top than at the bottom, the parts between said grooves having substantially flat faces for engagement with the material to be 40 glued, the grooves being about .04 inch or more deep, about .05 inch wide at the top and about 10 to the inch, and an adjustable scraper coöperating with said roll to regulate the quantity of glue applied whereby a substantially 45 continuous coating of glue will be applied.

2. The combination of a glue applying roll grooved longitudinally and arranged to apply the glue evenly and directly to the 50 surface to be glued, the parts between said grooves having substantially flat faces for engagement with the material to be glued, the grooves being about .04 inch or more deep, about .05 inch wide at the top and about 55 10 to the inch, and a scraper coöperating with said roll to regulate the quantity of glue applied, whereby a substantially continuous coating of glue will be applied.

3. The combination of a glue applying 60 roll having substantially parallel grooves, and arranged to apply the glue evenly and directly to the surface to be glued, the grooves having curved bottoms which merge into the side walls thereof, the side walls 65 tapering outwardly so that the grooves are

wider at the top than at the bottom, the parts between said grooves having substantially flat faces for engagement with the material to be operated upon, the grooves being at least .02 inch deep and at least .03 inch 70 wide and from 8 to about 12 to the inch and an adjustable scraper coöperating with said roll to regulate the quantity of glue applied.

4. The combination of a glue applying roll having substantially parallel grooves, and 75 arranged to apply the glue evenly and directly to the surface to be glued, the parts between said grooves having substantially flat faces for engagement with the material to be operated upon, the grooves being at 80 least .02 inch deep and at least .03 inch wide and from 8 to 16 to the inch, and a scraper coöperating with said roll to regulate the quantity of glue applied, whereby a substantially continuous coating of glue will be 85 applied.

5. The combination of a glue applying roll having substantially parallel grooves, and arranged to apply the glue evenly and directly to the surface to be glued, the 90 grooves having curved bottoms which merge into the side walls thereof, the side walls tapering outwardly so that the grooves are wider at the top than at the bottom, the grooves being at least .02 inch deep and at 95 least .03 inch wide and from 8 to 16 to the inch, and an adjustable scraper coöperating directly with said roll to regulate the quantity of glue applied, whereby a substantially continuous coating of glue will be applied. 100

6. The combination of a glue applying roll having substantially parallel grooves and arranged to apply the glue evenly and directly to the surface to be glued, the grooves being at least .02 inch deep and at 105 least .03 inch wide and from 8 to about 12 to the inch, and an adjustable scraper coöperating directly with said roll to regulate the quantity of glue applied, whereby a substantially continuous coating of glue will be applied. 110

7. The combination of a glue applying roll having substantially parallel grooves, and arranged to apply the glue evenly and directly to the surface to be glued, the 115 grooves having curved bottoms and side walls tapering outwardly, so that the grooves are wider at the top than at the bottom, the parts between said grooves having substantially flat faces for engagement with 120 the material to be operated upon, the grooves being from .02 inch to .06 inch deep, from .03 inch to .08 inch wide and from 8 to about 12 to the inch, and an adjustable scraper coöperating with said roll to regulate the 125 quantity of glue applied.

8. The combination of a glue applying roll having substantially parallel grooves, and arranged to apply the glue evenly and directly to the surface to be glued, the 130

- grooves having side walls tapering outwardly, so that the grooves are wider at the top than at the bottom, the parts between said grooves having substantially flat faces
- 5 for engagement with the material to be operated upon, the grooves being from .02 inch to .06 inch deep, from .03 inch to .08 inch wide and from 8 to 16 to the inch and an adjustable scraper coöperating with said roll to regulate the quantity of glue applied.
- 10 9. The combination of a glue applying roll having substantially parallel grooves, and arranged to apply the glue evenly and directly to the surface to be glued, the 15 grooves having curved bottoms and the parts between said grooves having substantially flat faces for engagement with the material to be operated upon, the grooves being from .02 inch to .06 inch deep, from .03 inch to .08 inch wide and from 8 to about 12 to the 20 inch and an adjustable scraper coöperating with said roll to regulate the quantity of glue applied.
10. The combination of a glue applying 25 roll having substantially parallel grooves, and arranged to apply the glue evenly and directly to the surface to be glued, the grooves having curved bottoms and side walls tapering outwardly so that the grooves 30 are wider at the top than at the bottom, the grooves being from .02 inch to .06 inch deep, from .03 inch to .08 inch wide and from 8 to about 12 to the inch, and a scraper coöperating with said roll to regulate the quantity 35 of glue applied.
11. The combination of a glue applying 40 roll having substantially parallel grooves, and arranged to apply the glue evenly and directly to the surface to be glued, the grooves being from .02 inch to .06 inch deep, from .03 inch to .08 inch wide and from 8 to about 12 to the inch and an adjustable scraper coöperating with said roll to regulate the quantity of glue applied.
- 45 12. The combination of a glue applying roll having substantially parallel grooves,

and arranged to apply the glue evenly and directly to the surface to be glued, the grooves being from .03 inch to .08 inch wide and from 8 to about 12 to the inch and an 50 adjustable scraper coöperating directly with said roll to regulate the quantity of glue applied.

13. The combination of a glue applying 55 roll grooved longitudinally, and arranged to apply the glue evenly and directly to the surface to be glued, the parts between said grooves having substantially flat faces for engagement with the material to be glued, the grooves being about 10 to the inch and an 60 adjustable scraper coöperating directly with said roll to regulate the quantity of glue applied, whereby a substantially continuous coating of glue will be applied.

14. The combination of a glue applying 65 roll having substantially parallel grooves, and arranged to apply the glue evenly and directly to the surface to be glued, the grooves being between 6 and 16 to the inch and a scraper coöperating with said roll to 70 regulate the quantity of glue applied, whereby a substantially continuous coating of glue will be applied.

15. The combination of a glue applying 75 roll having substantially parallel grooves, and arranged to apply the glue evenly and directly to the surface to be glued, the parts between said grooves having substantially flat faces for engagement with the material to be operated upon, the grooves being from 80 .03 inch to .08 inch wide and from 8 to about 12 to the inch and an adjustable scraper coöperating with said roll to regulate the quantity of glue applied.

In testimony whereof I have signed my 85 name to this specification this 8th day of June, 1917, at South Bend, Indiana.
